DISPLAY DEVICE

Fred Kerwer, Little Neck, N. Y., assignor to
Douglas Leigh, Inc., New York, N. Y.

Application May 2, 1946, Serial No. 666,670

2 Claims. (Cl. 40—127)

1

This invention relates to a display device for use on display surfaces such as bill boards or other rigid and non-rigid surfaces, and including the flexible envelopes of dirigibles and other lighter-than-air vehicles.

Advertising devices for use on the above mentioned surfaces have previously been provided. There have been serious disadvantages however in making practical use of these devices for several reasons including their weight and their cumbersome and expensive construction. Furthermore, the inherent rigidity of the former devices have rendered them unsuitable for use in connection with non-rigid surfaces such as are possessed by balloons and dirigibles.

Accordingly, it is an object of this invention to provide a display device which can be easily assembled on a surface, whether rigid or non-rigid, with low cost and speed of assembly and disassembly, and with relatively great reduction in the weight of the device compared with modern previous installations.

It is further an object to provide a device which has the above advantages and is especially suitable for attachment to flexible non-rigid envelopes of air-ships and dirigibles.

A further object is to provide a device which can be attached to a surface without the use of the usual heavy and cumbersome supporting frame-work hitherto required.

A further object of this invention is the provision of a display device of the character described which may be mounted directly upon the envelope of lighter-than-air aircraft, without the necessity of having to interpose a frame-work between said device and the envelope or the frame of the envelope.

Still another object of this invention is the provision of a display device of the character described which may be constructed of standard readily available equipment, which need not in any way be altered or modified to adapt it for the purposes set forth.

Preferred embodiments of this invention are shown in the accompanying drawing in which—

Fig. 1 is a side elevational view of an anchored display balloon incorporating the display device herein claimed;

Fig. 2 is a fragmentary section on the line 2—2 of Fig. 1;

Fig. 3 is an enlarged fragmentary view of the lamps shown in Figs. 1 and 2, showing how they are fastened to the envelope of the balloon;

2

Fig. 4 is a sectional view on the line 4—4 of Fig. 3;

Fig. 5 is a sectional view on the line 5—5 of Fig. 3;

Fig. 6 is an enlarged fragmentary prospective view of one of the lamps used in this device;

Fig. 7 is a side elevational view of a small dirigible or blimp embodying this device;

Fig. 8 is an enlarged fragmentary view of a device of the character described which may be used as a travelling or changing sign; and

Fig. 9 is a fragmentary view of a second embodiment of this invention.

15 The device herein claimed comprises a plurality of electric light bulbs 10 mounted in sockets 11 and connected to each other and to a source of electric current by means of wire conductors 12. These conductors are relatively

20 flexible and are insulated in the usual manner. The bulbs are relatively small and of low voltage. They are arranged on the envelope 13 of the balloon shown in Fig. 1 and on the envelope 14 of the dirigible shown in Fig. 7 in accordance with any predetermined pattern. Thus in Fig. 1 they are arranged to spell the name Doe and in Fig. 7 they are arranged to spell the name John Doe. It will be understood that any other arrangement is herein contemplated

25 30 whether a name or a word is spelled out or a symbol or a picture is represented.

Bulbs 10 are held in place by means of flexible patches 20 which affix the conductors 12 to the envelope. Patches 20 are made preferably of the same kind of sheet material or fabric of which the envelope itself is made. They may be circular or rectangular or of any other shape. These patches are affixed to the envelope by means of an adhesive in the same manner as conventional finger patches 22 are affixed to the envelope.

40 45 It will be seen from the foregoing that no frame is required on which to mount bulbs 10. Instead the conductors 12 themselves constitute the necessary framework or supports for mounting the bulbs.

As is well known, the envelope of a balloon and of a dirigible constitutes a non-rigid element. It vibrates and flexes and engages in other forms of distorting movement. The patches 20 being made of substantially the same material as are the envelopes 13 and 14 are inherently adapted to engage in the same kind of vibratory or other movement. Consequently, 50 55 neither a distortion of the overall shape of the

balloon envelope in a high wind, nor a series of minor distortions such as waves in the envelope of the dirigible will have any adverse effect upon the structure supporting the bulbs. The nature of this structure furthermore adapts it to conform to the curvature of the side of the envelope. Thus it is immaterial whether the bulbs are to be mounted on a relatively flat surface or on a sharply curved surface. The same supporting structure is used in either case without modification or change.

It will be understood that the feeder wires in the balloon may be connected to a source of electric current situated on the ground. Insofar as the dirigible is concerned, a better practice is to provide the source of current in the form of a battery or generator carried within the cabin.

It is important to note at this point that by reason of the construction hereinabove described, letters and characters as well as pictures may be reproduced in a form several times larger than has heretofore been considered possible in connection with lighter-than-air aircraft. Thus for example, the letters shown on the dirigible in Fig. 7 may stand as much as 24 feet high in contrast to the letters of only 4 feet in height previously used. Furthermore, the 24-foot characters of the present device weigh less than the 4-foot characters of the signs now and previously in use.

In Fig. 8 an arrangement of bulbs is shown which may be used for travelling or changing sign purposes, as for flashing news bulletins or producing animated pictures. These bulbs are fastened to the envelope in the manner previously described and by the same means. They are hooked up by means of cables 30 to a selecting mechanism and source of electric current 31. This hook-up and this mechanism are conventional and are not herein claimed. Any type of control mechanism which may be used in conventional travelling signs may be used in the present display device. There is a weight limitation however and the preferred forms of this type of mechanism are those which weigh the least. Fig. 8 is not intended to disclose an actual wiring diagram. It is intended rather, merely to indicate that the bulbs in question are hooked up in the usual manner to a conventional control mechanism.

The device disclosed in Fig. 8 is the only device known to applicant which provides travelling signs and animated pictures on lighter-than-air aircraft. This has heretofore been deemed impossible of practical attainment.

A modified form of this invention is shown in Fig. 9 where the bulbs 10 are affixed to a substantially rectangular sheet of flexible material such as fabric 40 in the same manner as above described in connection with the envelope proper. A character such as a letter "E" is painted or otherwise applied to sheet 40. The bulbs 10 are arranged to outline said character. The painted character will be seen during the day and the character as outlined by the bulbs will be seen at night. The sheet 40

is attached to the envelope 41 by means of lacings 42 connected to finger patches 43. A different letter may be substituted for the letter "E" by the simple expedient of removing the sheet of fabric bearing the letter "E" and substituting another sheet therefor bearing said different letter. The conductors interconnecting the bulbs of each individual sheet 40 are connected to a source of electric current by means of a plug-in connection or by any other conventional means.

It will thus be clear that I have provided a simple, light-weight, economical device which will permit symbols or words, or letters to be displayed and illuminated upon a surface, whether rigid or non-rigid, which can be easily arranged to present a wide variety of letters and symbols, which can be easily and quickly attached, removed, and modified at will and greatly reduces the cost of the usual installation.

Preferred embodiments only of the invention herein claimed have above been described and it will be understood that changes and variations may be incorporated therein without departing from the basic principles and spirit of the invention.

I claim:

1. A display device which comprises a supporting surface, an electrical conductor disposed thereon and shaped in the form of a symbol to be displayed, light sockets disposed at intervals along said conductor, and means disposed between the sockets to adhesively fasten the conductor to the surface.

2. A display device which comprises a supporting surface, an electrical conductor thereon and disposed in the shape of a symbol to be displayed, light sockets disposed at intervals along said conductor to receive light bulbs therein, and cement patches disposed over the conductor between the sockets to firmly adhere the conductor to the surface.

FRED KERWER.
